UNITED STATES PATENT OFFICE

SANFORD J. LOCKE, OF SYRACUSE, NEW YORK, ASSIGNOR TO UNITED STATES HOFFMAN MACHINERY CORPORATION, OF NEW YORK, N. Y., A CORPORATION OF DELAWARE

PRESS

Application filed October 1, 1928. Serial No. 309,374.

This invention relates to pressing machines and particularly to the type embodying a buck and cooperating head used for garment and laundry pressing work.

5 While these machines are designed to cause the head to move as far as conveniently possible from the buck when the press is open there are limits to the separation possible and it is desirable to provide for occasional 10 extreme separation,—for example when the buck is to be used for steaming purposes and the head is functionless. To accomplish this result I interpose in the supporting and guiding mechanism for the head an element which 15 is shiftable when the press is open to carry the head to the rear and out of cooperative relation with the buck so that it is completely out of the way. I also provide releasable means to retain this member in normal position.

The preferred embodiment of the invention is illustrated in the accompanying drawings in which

Figure 1 is a side elevation of a press embodying the invention, the press being shown in full lines in its closed position and in dotted lines in its abnormal open position;

Figure 2 is a section on the line II—II of Figure 1 and drawn on an enlarged scale; 30 and Figure 3 an elevation, partly in section, showing certain portions of the mechanism.

A portion of the frame of the press is represented at 6 and the table at 7. 8 represents the usual buck; 9 the usual press head; and 35 11 the lever on which the press head 9 is mounted. The lever 11 is pivoted at 12 in the shiftable support 13 which in turn is pivoted at 15 on a portion of the frame 6.

The member 13 is shown in full lines in its 40 normal position in Figure 1 and may be latched in that position by a bolt 16 which is urged in engaging direction by a spring 17 and which may be retracted by a finger-piece 18. When the bolt is retracted the member 45 13 may be swung on the pivot 15 to the dotted line position of Figure 1 in which the head 9 is moved far away from the buck 8.

As will be seen upon reference to Figures 1 and 3, the lower end of the member 13 is 50 formed with a flat face 13^a designed to co-

operate with a face 6^a formed upon the frame 6. This arrangement forms a stop for the parts and inasmuch as the member 13 and the head-carrying lever and the head are to the rear of the pivot 15 the parts will remain in that position. In other words, the parts are thrown to the rear of the vertical line passing through the pivot. Member 13 is provided with a stop 10 designed to cooperate with the outer end of the lever 11 when the parts are 60 brought to the dotted line position, Figure 1, or when the lever 11 is rocked about the pivot 12 in the normal operation of the press.

The lever 11 may be actuated in any known manner and I illustrate the toggle link 19 and a portion of a companion toggle link 21 as representative of a mechanism familiar in this art. 22 is a counter balance spring; 23 the handle by means of which the head is drawn down; 24 a steaming valve; 70 and 25 a finger-piece for opening the valve against the resistance of the return spring 26.

In the normal operation of the device bolt 16 engages the member 13 as shown in Figure 2 and holds the member 13 in its forward 75 position;—that is the full line position of Figure 1. Under such circumstances the lever 11 rocks on the fulcrum 12 to carry the head 9 into and out of contact with the buck 8.

The press may be closed by hand or 80 through the toggle links 19 and 21 as is familiar in the art. When the press is open, and without disengaging the links 19 and 21, the bolt 16 may be withdrawn by pulling on the finger-piece 18. It then becomes possible 85 to swing the member 13 to its rearward dotted line position (see Figure 1), in which position it is held by spring 22 and gravity. At this time the press head is inoperative.

When it is desired to resume operations 90 the member 13 is drawn forward and when it reaches its normal position the bolt 16 snaps into place and locks it in position.

While I have shown the invention applied to a press of the lever type it is obviously not 95 limited in its applicability to this type of press but may be adapted, with minor modifications, to any press having a head and buck with some supporting and guiding means for the head. While this supporting and guid-

ing means may assume various different forms it may obviously be rendered shiftable according to the present invention to permit the shifting of the head to an abnormal and inoperative position.

5 The exact mechanism used to hold the supporting and guiding means in its normal position is not material. The latch bolt illustrated is a convenient and inexpensive expedient but various substitutes are possible.

10 What is claimed is:

1. In a press, the combination of a buck; a head, movable into and out of pressing engagement with the buck; a guiding and supporting means for the head, said means having a normal and an abnormal position, in the latter of which the head is out of cooperative relation with the buck; means for locking said means in a fixed normal position; and means independent of the locking means for moving the head into open and closed positions.

2. In a press, the combination of a head; a buck; a shiftable member on which said head is mounted; a guiding element for said shiftable member, said guiding element being shiftable between a normal position and an abnormal position with the head inoperative; means for latching said guiding element in a fixed normal position; and means independent of the latching means for moving the head into open and closed positions.

3. In a press, the combination of a head; a buck; a lever on which the head is mounted; a member on which the lever is pivoted, said member being shiftable from a normal position to an abnormal position in which the head is displaced further from the buck; releasable means for securing said member in a fixed normal position; and means independent of said releasable means for moving the head into open and closed positions.

4. In a press, the combination of a head; a buck; a shiftable member in which said head is mounted; a linkage connected to actuate said member; a guiding element for said shiftable member, said guiding element being shiftable while the press is open from normal position to a position in which the head is abnormally displaced from the buck, while still connected with said linkage; and means for securing said shiftable guiding element in a fixed normal position, said means being independent of any connection with said linkage.

5. In a press, the combination of a head; a buck; a lever on which the head is mounted; a linkage connected with said lever to actuate the same; a member on which the lever is pivoted, said member being shiftable from a normal position to an abnormal position in which while the lever is still connected with the linkage, the head is abnormally displaced; and means for securing said member in a fixed normal position, said means being

independent of any connection with said linkage.

6. In a press, the combination of a main frame; a buck mounted thereon; a member pivotally connected at its lower end to the main frame and extending in a general vertical direction, said member and the frame being provided with cooperating stop faces adapted to engage when the member is thrown to the rear away from the buck; means for securing said member in fixed relation to the frame when said member is rocked forwardly; a lever fulcrumed upon the upper end of said member; a head carried by the forward end of the lever and designed to cooperate with the buck; and means for actuating said lever, said means being independent of said securing means.

7. In a press, the combination of a main frame; a buck mounted thereon; a head; a lever to which said head is secured; a support for the lever, said support being pivotally connected at its lower end to the main frame and at its upper end to the lever; means for locking said support when the same is thrown forwardly; and means independent of said locking means for rocking the lever to bring the movable head into and out of pressing relation with the buck.

8. In a press, the combination of a main frame; a buck mounted thereon; a head; a lever to which said head is secured; a support for the lever, said support being pivotally connected at its lower end to the main frame and at its upper end to the lever; means to limit the rearward swinging movement of the support; means for locking said support when the same is thrown forwardly; and means independent of said locking means for rocking the lever to bring the movable head into and out of pressing relation with the buck.

In testimony whereof I have signed my name to this specification.

SANFORD J. LOCKE.
